UNITED STATES PATENT OFFICE.

LOUIS STOCKER, OF STITHTON, KENTUCKY.

YARN-WINDING MACHINE.

1,389,392.

Specification of Letters Patent. Patented Aug. 30, 1921.

Application filed July 24, 1920. Serial No. 398,617.

To all whom it may concern:

Be it known that I, LOUIS STOCKER, a citizen of the United States, residing at Stithton, in the county of Hardin and State 5 of Kentucky, have invented new and useful Improvements in Yarn-Winding Machines, of which the following is a specification.

This invention relates to yarn winding machines for winding yarn on tubes to color 10 the same, the principal object of the invention being to provide means for twisting the yarn as it is being wound upon the tubes in such a way that after the yarns are drawn off the tubes there will be no twist left in 15 them and all the ends will have the same tension and there will be no slack ends as is the case when the yarn is wound on a common winder.

Another object of the invention is to provide means whereby the yarn is twisted in 20 one direction as it is being wound upon the tube from one end to the other and in an opposite direction as it is being wound upon the tube in an opposite direction.

25 A further object of the invention is to provide means whereby the twisting mechanism is moved in a path parallel to the tube carrying roller and is then automatically caused to travel back over this path, such 30 means comprising a worm shaft engaging a worm nut carried by the twisting mechanism for changing the direction of rotation of the worm shaft at each end of the travel of the twisting mechanism.

35 This invention also consists in certain other features of construction and in the combination and arrangement of the several parts, to be hereinafter fully described, 40 illustrated in the accompanying drawings and specifically pointed out in the appended claims.

In describing my invention in detail, reference will be had to the accompanying drawings wherein like characters denote 45 like or corresponding parts throughout the several views, and in which:

Figure 1 is a front view of the invention.

Fig. 2 is a plan view.

Fig. 3 is an end view.

50 Fig. 4 is a section on line 4-4 of Fig. 2.

Fig. 5 is a section on line 5-5 of Fig. 2.

Fig. 6 is an enlarged view showing the details of the twisting device.

Fig. 7 is an enlarged view of the belt shifting mechanism.

Figs. 8 and 9 are detail views.

Fig. 10 is a view of a modification. In these views 1 indicates the frame of the apparatus in which is journaled the shaft 2 which carries the fluted roller 3. This shaft 60 is connected with the main drive shaft 4 by the gears 5, the main shaft 4 being provided with the fast and loose belt pulleys 6. Vertically movable weights 7 engage the uprights 8 and the tube shaft 9 has its reduced 65 ends engaging recesses 10 formed in the lower ends of said weights so that the tube on said shaft is pressed into engagement with the fluted roller by said weights. The weights may be held in any desired position 70 upon the uprights 8 by means of the eccentric 75 carried by each weight and adapted to be moved into and out of engagement with the lined plate 12 by the lever 13. This lever is held in position with the eccentric 80 pressing the plate against the upright by means of a spring 14 which has one end connected with the weight and its other end to an adjustable clip 15 movable in a slot 16 formed in said lever.

80 A worm shaft 17 is also mounted in the frame in front of the fluted roller and this shaft is connected with the pulley shaft 18 by means of the gears 19, said shaft 18 being provided with the loose pulleys 20 and 85 the fast pulley 21, these pulleys being connected with the pulleys 6 by the belts 22. A worm member 23 engages with the worm shaft 17 and this member is held against rotation by means of an arm 24 thereon engaging 90 with a sleeve 25 which is slidably mounted on the shaft 18. The member 23 carries a circular upright frame 26 in which is rotatably mounted, preferably by ball bearings, a disk 27 which is provided with 95 the openings 28 through which the yarns are adapted to be threaded. This disk has connected therewith a circular rack 29 which engages a rack bar 30 carried by the frame and arranged parallel to the shaft 17. An 100 arm 31 is connected with the member 23 and this arm has its free end bent upwardly and provided with a guiding eye 32.

In order to cause the worm shaft 17 to rotate in a reverse direction when the worm 105 member 23 nears the end thereof I provide therewith belt shifting means for reversing the rotation of the shaft 18. Such means include a longitudinally movable shifter bar 33 mounted in guides in the frame and having a pair of loops 34 therein for engaging the belts. As shown one of these belts is

crossed so that as this cross belt is moved into engagement with the fast pulley the shaft 18 will be driven in one direction and when the straight belt is placed in engagement with the fast pulley 21 the shaft 18 is driven in an opposite direction. When either belt is engaging with the fast pulley the other belt is placed on one of the loose pulleys by the shifter mechanism. The 10 bar 33 is connected by a link 35 with a rotatable disk 36, located on a shaft 37. This shaft 37 is provided with a beveled gear 38 which meshes with a gear 39, loose on shaft 40 which is geared to shaft 18 by the gears 41. 15 The gear 39 is connected to one end of a coil spring 42 the other end of which is connected with an adjustable collar 43 located on shaft 40. Thus when the shaft 40 is rotated by shaft 18 the spring will be wound up and 20 cause the gear 39 to rotate the shaft 37 and the disk by the gear 38. This movement of the disk is prevented, however, by means of a latch bar 44 engaging one of a pair of projections 45 formed on the periphery of the 25 disk 36. The latch bar is adapted to move out of engagement with said projections by a trigger 46 pivotally mounted on the disk and provided with a pair of arms 47 for engaging said latch bar. This trigger is actuated by the twisting mechanism by means 30 of a longitudinally movable rod 48 having stops 49 thereon for engaging the trigger and other stops 50 which are adapted to be struck by the worm member 23 as said member nears the end of its travel in either 35 direction.

The yarns are passed through the holes in disk 27 and through eye 32 and are passed around the tube on shaft 9. The weights 40 are then lowered to press the tube against the fluted roller and then the belts are shifted to cause the winding mechanism to travel from one end of the worm shaft to the other. The fluted roller will be rotated at the same 45 time so as to wind the yarns on the paper tube. As the worm member 23 travels along the worm shaft the disk 27 will be revolved by its rack engaging the rack 30 and thus the yarns will be twisted. As soon as the 50 winding mechanism nears one end of its movement the member 23 will strike one of the stops 50 so as to move the rod 48 longitudinally and cause one of the stops 49 to strike the trigger and cause said trigger 55 to move the latch bar out of engagement with the projection on the disk. This will free said disk and permit the spring 42 to rotate the same and this movement of the disk will direct its connection with the 60 shifter bar 33, move said bar to shift the belts and thus reverse the rotation of the shaft 18 and the worm shaft. Thus the worm member 23 will return to its starting point and then disk 27 will be rotated in a 65 reverse direction. Thus the yarn will be

twisted one way as long as the twisting mechanism moves from one end of the tube to the other and in the other direction the twister is reversed so that after the yarns are drawn off from the tube there will be no 70 twist left and the yarns will have the same tension and there will be no slack ends hanging down as is the case when the yarn is wound on a common winder.

In the modification I substitute an endless chain 51 for the worm shaft and bolt the yarn guide to this chain. The chain passes over a flange pulley 52 and a sprocket wheel 53. The sprocket wheel 53 is carried by shaft 54 which is geared to the pulley shaft 55 by the gears 56. In other respects this modification is the same as that above described.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. In combination with a yarn winding machine, a winding roller, a reciprocating member, means for reciprocating said member in a path parallel to the roller, a twister member carried by the reciprocating member and means for rotating the twisting member in one direction as the reciprocating member is moved in one direction and for rotating the twisting member in an opposite direction on the return movement of the reciprocating member.

2. In combination with a yarn winding machine, a reciprocating member, a rotatable wheel carried thereby, and having openings therein through which the yarn passes, an annular rack connected with said wheel and a rack bar with which the annular rack engages in the reciprocation of said member.

3. A yarn winding machine comprising a reciprocating member, a rotatable wheel carried thereby and having openings therein through which the yarn passes, an annular rack on said wheel, a rack bar with which the annular rack engages in the reciprocation of said member and means for automatically changing the direction of movement of said member.

4. A yarn winding machine comprising a reciprocating member, a rotatable wheel carried thereby and having openings therein through which the yarn passes, an annular rack connected with said wheel, a rack bar with which the annular rack engages in the reciprocation of said member, an arm connected with said member and having a guid-

ing eye therein and means for reciprocating said member, such means including a belt driven shaft, and belt shifting means actuated by the movement of the reciprocating member.

5. In combination with a yarn winding machine, a fluted roller, means for rotating the same, a shaft adapted to carry a tube

upon which the yarn is to be wound, weighted means for holding said shaft with the tube thereon engaging the roller and means for holding the weighted means and the shaft in raised position above the fluted roller.

In testimony whereof I affix my signature.
LOUIS STOCKER.
